UNITED STATES PATENT OFFICE.

EDWARD F. HERSCHEDE, OF CINCINNATI, OHIO.

CLASP.

1,225,710.

Specification of Letters Patent. Patented May 8, 1917.

Application filed May 22, 1916. Serial No. 99,008.

To all whom it may concern:

Be it known that I, EDWARD F. HERSCHEDE, a citizen of the United States of America, and resident of Cincinnati, in the 5 county of Hamilton and State of Ohio, have invented a new and useful Improvement in Clasps, of which the following is a specification.

This invention relates to an improved 10 clasp and particularly to a clasp for bracelets, necklaces and other articles of jewelry, as well as for belts and the like.

An object of my invention is to produce 15 a clasp adapted to render adjustable as to size, the article attached thereto, in addition to performing the function of detachably uniting the extremities of an article or of uniting two or more articles in the placing of the article or articles in condition for use.

20 A further object is to produce an improved clasp in which the attaching of one member of the clasp to the coöperating member of the clasp is attained by locking means adapted to prevent inadvertent detachment 25 of one member from the other member.

A further object is to produce an adjustable clasp which may be secured in any adjusted position on a mounting strap, strip, ribbon, tape, or braid without injuring the 30 material thereof.

These and other objects are attained in the clasp described in the following specification and illustrated in the accompanying drawings, in which;

35 Figure 1 is an enlarged plan view of a clasp embodying my invention, the members thereof being secured together.

Fig. 2 is a plan view of the clasp shown in Fig. 1, showing the members in the first 40 position to which they are brought in fastening them together, or the last position to which they are brought in separating them.

Fig. 3 is an inverted plan or under side view of the clasp, showing the adjustable 45 member thereof locked in position on its mounting strap.

Fig. 4 is a side elevation of the clasp shown in Fig. 1.

Fig. 5 is a sectional view taken on the 50 line 5—5 of Fig. 1.

Fig. 6 is a sectional view taken on the line 6—6 of Fig. 4, showing an end elevation of the clasp in position on its mounting strap.

The clasp embodying my invention is 55 preferably made of metal and consists of a body portion 7 constructed in the form of a sleeve adapted to embrace one end of the mounting strap 8 to which it is to be secured. The opening of this sleeve is sufficient to receive the strap 8 and the wedge 9 between the under surface of the strap and the bottom 10 of the sleeve. The wedge is provided with pins 11 which engage slots 12 formed in the bottom of the sleeve. These 60 slots coöperate with the pins in limiting the motion of the wedge with relation to the sleeve and in preventing displacement and loss of the wedge from the sleeve when it is moved to its loosened position. By means 65 of this construction the wedge may be moved from its locking position as disclosed in Figs. 3 to 5 inclusive, until the pins engage the opposite ends of the slots and permit of reciprocation of the sleeve on its mounting 70 end of the strap.

The top 13 of the sleeve is provided with pins 14, the pins having heads 15 formed thereon. These pins coöperate with slots 16 formed in a plate 17 forming the coöperating member of the clasp and secured to the opposite end of the strap mounting the adjustable sleeve 7. The slots are shaped substantially like key holes, enlargements 18 being provided at one end for passage of the 85 heads 15 of the pins 14 therethrough, the narrow portions 19 of the slots being provided for the passage of the shanks 20 of the pins therethrough. I prefer making the enlargements 18 somewhat smaller than the 90 heads 15 by means of spring fingers 21 formed integrally with the plate, so that when the pins are passed through the enlargements 18 of the plate, the fingers 21 will yield as shown in Fig. 2, the fingers 95 returning to their normal positions as shown in Fig. 1, immediately after passage of the heads 15 through the enlargements. After the heads have passed through the enlargements the shanks 20 may be passed through 100 the elongated portions 19 of the slots to the opposite ends thereof in order to bring the plate 17 to its locked position with relation to the sleeve 7. Removal of the plate from its locked position with relation to the 105 sleeve is had by reversing the operation just described, the enlargements 18 of the slots being brought to register with the heads 15

of the pins and then the plate lifted to cause the fingers 21 to yield and permit the passage of the pins through the enlargements.

The mounting strap to which the members 5 of the clasp are secured, may be of metal, either thinly rolled or woven in the form of a metal fabric, or the strap may be of fabric or other fibrous material such as leather, the clasp coöperating efficiently with straps of 10 any material.

In employing the clasp for fastening the ends of bracelets together, the sleeve is adjusted and secured to one end of the strap and the plate comprising the coöperating member of the clasp and which is permanently secured in any suitable manner to the opposite end of the strap, is brought into locking engagement with the pins of the sleeve as above described. If it is found 15 that the bracelet is too tight or too loose the parts of the clasp may be disengaged and the sleeve may be adjusted along its mounting end of the strap to the position in which the length thereof is rendered correct. The 20 wedge is then moved to its sleeve-locking position and the bracelet is then ready for use. In the use of my improved clasp as a fastening means for the ends of belts, the material of the strap would probably be 25 of leather, for which use the clasp would be designed along much larger and heavier lines of construction, similar to the construction shown in the drawings. However, when the clasp is to be employed for necklaces in which the strap of material upon 30 which it is mounted, is of extremely narrow width and of rather delicate construction, the clasp may very well consist of but one pin mounted on a sleeve of correspondingly 35 minute construction, with the plate suitably designed for coöperation therewith and having but one slot for engaging the pin.

Although I have shown but one design 40 for my improved clasp the novel principles of construction need not be changed to embody therewith designs possessing varying 45 ornamental characteristics, such as would be demanded for jewelry. Furthermore, the manner of permanently securing the plate to 50 the opposite end of the strap, may be varied according to the material of which the strap is composed. If the strap is of fabric it may be readily sewed to the plate, I having shown a bar 22 about which the end of the 55 strap may be looped for such a purpose. If the strap is of other fibrous material such as leather, it may be similarly secured, and if the strap is of metal, whether it be woven or in a thin strip, the plate may be soldered

thereto, gold, silver, or other soldering cor- 60 responding to the metal of the strap, being employed for this purpose.

In addition to this, the construction may be further modified by eliminating the spring-like fingers 21, the enlargements 18 65 in such a modification being of the same size as the heads 15 of the pins in order to permit of their passage through the enlargements, the plate 17 having merely a slot or series of slots shaped like a key hole. 70

It will be seen that in my improved construction I have provided a clasp which will not injure the material of the strap to which it is secured no matter how often and how tightly the wedge be moved to lock the 75 sleeve in its adjusted positions on the end of the strap. This is a marked advantage over constructions heretofore employed, such as buckles and the like which have members adapted to enter perforations in the strap 80 or which are provided with teeth which embed themselves into the material of the strap and thereby eventually injure it.

Having thus described my invention, what I claim is:

85

1. In a clasp, the combination of a sleeve, a coöperating member, and means for frictionally securing the sleeve upon a strap end, the sleeve being adapted to receive the strap end, and the coöperating member being adapted to be located at another strap end.

2. In a clasp, the combination of a sleeve, a coöperating member, and a wedge for frictionally securing the sleeve upon a strap 95 end, the sleeve being adapted to receive the strap end, and the coöperating member being adapted to be located at another strap end.

3. In a clasp, the combination of a sleeve 100 adapted to receive a strap end, a pin secured to the strap end, and a plate having an aperture to receive the pin and being adapted to be secured to another strap end.

4. In a clasp, the combination of a sleeve 105 adapted to receive a strap end, means for frictionally securing the sleeve upon the strap end, a pin secured to the sleeve and a plate having a slot therein and having spring fingers projecting into the slot and 110 adapted to yield to pass the head of the pin.

In testimony whereof, I have hereunto subscribed my name this 19th day of May, 1916.

EDWARD F. HERSCHEDE.
